(57) **CLAIM**

We claim the design for a voice synthesizer, as shown and described.

DESCRIPTION

FIG. 1 is a downward, frontward, rightward isometric view of a voice synthesizer according to our design;

FIG. 2 is a top plan view thereof;

FIG. 3 is a leftward elevational view thereof;

FIG. 4 is a bottom plan view thereof;

FIG. 5 is a rightward elevational view thereof;

FIG. 6 is a front elevational view thereof; and,

FIG. 7 is a rear elevational view thereof.
